Primary Examiner — Ian Simmons*Assistant Examiner* — Charles Hanson(74) *Attorney, Agent, or Firm* — Fish & Richardson P.C.(57) **CLAIM**

The ornamental design for an implantable blood pump, as shown and described.

DESCRIPTION

FIG. 1 is a perspective view of an implementation of a new ornamental design of an implantable blood pump.

FIG. 2 is a left side view of the design of FIG. 1.

FIG. 3 is a right side view of the design of FIG. 1.

FIG. 4 is a front view of the design of FIG. 1.

FIG. 5 is a back view of the design of FIG. 1.

FIG. 6 is a top view of the design of FIG. 1; and,

FIG. 7 is a bottom view of the design of FIG. 1.

The broken line showing is included for the purpose of illustrating environment and forms no part of the claimed design.
